DOLLY FOR HANDLING ROLLS OF CARPETING

George A. Kirkpatrick, 105 W. Ridgecrest Blvd.,
Ridgecrest, Calif. 93555

Filed Oct. 6, 1970, Ser. No. 25,350

Term of patent 14 years

Int. Cl. D12—02

U.S. Cl. D14—3

Fig. 1

Fig. 4

FIG. 1 is a three-quarter front perspective view of a dolly for handling rolls of carpeting embodying my new design;

FIG. 2 is a side elevation of the same;

FIG. 3 is a top plan view; and

FIG. 4 is an end view of the dolly.

I claim:

The ornamental design for a dolly for handling rolls of carpeting, as shown.
